United States Patent Office

Des. 175,681
Patented Sept. 27, 1955

175,681

VEHICLE LIGHT

George D. Hart, Cincinnati, Ohio, assignor to Northwest Capital Corporation, New York, N. Y., a corporation of New York

Application May 20, 1955, Serial No. 36,137

Term of patent 14 years

(Cl. D48—32)

Fig. 1

Fig. 2

Fig. 3

Fig. 4

Figure 1 is a perspective view of a vehicle light showing my new design.

Figure 2 is a top plan view thereof.

Figure 3 is a front elevational view thereof.

Figure 4 is a side elevational view thereof, partly broken away and in section.

I claim:

The ornamental design for a vehicle light, substantially as shown.
